UNITED STATES PATENT OFFICE.

CHARLES P. MOSHER, OF PHILADELPHIA, PENNSYLVANIA, ASSIGNOR TO
THE ENTERPRISE MANUFACTURING COMPANY OF PENNSYLVANIA,
OF SAME PLACE.

DESIGN FOR A SAD-IRON HANDLE.

SPECIFICATION forming part of Design No. 33,662, dated December 4, 1900.

Application filed November 10, 1900. Serial No. 36,130. Term of patent 14 years.

To all whom it may concern:

Be it known that I, CHARLES P. MOSHER, a citizen of the United States, residing in Philadelphia, Pennsylvania, have invented and produced a certain new and original Design for a Sad-Iron Handle, of which the following is a specification.

My design for a sad-iron handle is clearly illustrated in the accompanying drawing, which represents the handle in perspective.

The essential feature of the design is the ornamental side extension projecting from the central portion of the base of the handle.

H is the base of the handle.

15 H' is the handhold.

H² is the ornamental side extension, connected to the central portion of the base of the handle by an arm h. The side extension H² has a central opening h', as shown.

I claim—

20 The design for a sad-iron handle as herein described and as illustrated in the accompanying drawing.

In testimony whereof I have signed my name to this specification in the presence of 25 two subscribing witnesses.

CHARLES P. MOSHER.
